Lewison & Thompson, ATTORNEYS

UNITED STATES PATENT OFFICE.

HENRY W. COOK, OF SYRACUSE, NEW YORK.

LEGGING.

1,272,386.

Specification of Letters Patent. Patented July 16, 1918.

Application filed April 15, 1918. Serial No. 228,627.

To all whom it may concern:

Be it known that I, HENRY W. COOK, a citizen of the United States of America, and resident of Syracuse, in the county of Onondaga, in the State of New York, have invented new and useful Improvements in Leggings, of which the following, taken in connection with the accompanying drawings, is a full, clear, and exact description.

10 This invention relates to certain improvements in leggings and is particularly designed for and illustrated in connection with a fabric legging for army use.

15 The object of the invention is to provide a highly efficient, easily operable, rigid, positive, adjustable connection for a foot or instep strap in connection with a legging, permitting adaptation of the legging to shoes of various sizes, rapid and easy securing of the legging to the foot, and the positive retention of the legging in predetermined position with relation to the strap.

20 Other objects and advantages will appear from the following description taken in connection with the accompanying drawings, in which—

Figure 1 is an elevation of a legging constructed in accordance with this invention.

Fig. 2 is a cross section on line 2—2, 30 Fig. 1.

Fig. 3 is a view of the plate with centrally arranged stud and slots or openings upon opposite sides of the stud.

Fig. 4 is a view of the eyelet for connecting the plate to the fabric of the legging.

Fig. 5 is a view of a modified form of plate.

The legging as shown, comprises a fabric body —1— open at one side and provided with lacing means —2— extending from top to bottom of the legging.

Near the bottom of the legging, and preferably at the closed side thereof, is secured one end —3— of a foot or ankle strap —4—, the opposite end of which, in this specific embodiment, is adapted for positive, removable, adjustable engagement with the opposite side of the legging to provide a loop for engaging the foot of the wearer, and for this purpose the strap is provided with a series of spaced openings, preferably containing eyelets —5— of rigid or semi-rigid material, as metal.

55 The strap —4—, as shown, may perhaps preferably be formed of two thicknesses of material, and as illustrated comprises a strip

of fabric and a strip of leather secured together in any suitable way, as by stitching along their longitudinal edges.

For the purpose of effecting removable engagement of the free end of the strap with the legging, a plate-like member —6— is placed in contact with the inner surface of the lower portion of the open side of the legging and substantially opposite the end —3— of the strap —4—.

The plate —6— is provided with a stud —7— which extends outwardly through the fabric body —1— of the legging. The plate is further provided with a pair of slots disposed upon opposite sides of the stud —7— and arranged one above the other vertically of the legging, and the fabric body is provided with openings registering with these slots.

75 Eyelets —8— of suitable material, as metal, are extended through the registering openings in the fabric and the slots —9— in the plate.

80 Preferably these eyelets are formed with a base flange —10— and a tubular elongated or oval shaped body —11— extending at right angles thereto, the body —11— being passed inwardly through a registering opening in the fabric and slot —9—.

85 The base flange —10— comes in contact with the outer surface of the fabric and the inner edge of the body —11—, as extended through the slot —9— in plate —6—, may be riveted or bent into contact with the plate to constitute a permanent securing means as well as a smooth, hard, permanent surface for the passage of the strap —4—.

The free end of the strap —4— is secured to the open side of the legging by passing the end outwardly from the interior of the legging through the lower eyelet —8—.

90 Any desired one of the eyelets —5— may be brought into registration with the stud —7— and passed downwardly over the stud by extending the free end of the strap inwardly from the exterior of the legging through the upper eyelet —8— to the interior thereof.

95 The connection thus made between the strap and legging is of a positive and rigid character which does not permit relative movement of the two parts. The portions of the strap within the legging prevent 100 harmful contact of plate —6— with the shoe of the wearer.

The connection is easily and rapidly made and is adjustable to various size wearers, and after adjustment may be permitted to remain in permanently arranged position.

- 5 The structure is of neat appearance avoiding the extension of loose ends exterior of the legging.

In Fig. 5, I have illustrated a modified form of stud. In this particular construction, the stud —12— is provided with an enlarged head preferably of a resilient character, and in this particular illustration the enlarged head is of substantially spherical form and is split, vertically to permit contraction and expansion of the same.

When such a stud is forced through eyelet —5—, its removal is less easily effected than is the case with the plain cylindrical stud of former figures.

20 It will be understood that there are many various and well-known ways of producing a locking stud, as indicated in Fig. 5, and that the stud —12— is purely illustrative of one such construction.

25 Although I have shown and described one particular form and character of legging, I do not desire to limit myself to the details of the same, as various changes may be made without departing from the spirit 30 of this invention as set forth in the appended claims.

What I claim is:

1. A legging comprising a body portion, a plate in contact with the body portion, said plate and body portion provided with a plurality of spaced registering openings, a stud secured to the plate and extending through the body portion intermediate said spaced openings, eyelets passed through said registering openings and having flanged portions gripping the plate and the legging body for securing the parts together, and a strap having one end secured to the legging body and its opposite end extended successively through said eyelets and having an opening fitted over said stud.

2. A legging comprising a body portion, a plate in contact with the body portion, said plate and body portion provided with a plurality of spaced registering openings, a stud secured to the plate and extending through the body portion intermediate said spaced openings, eyelets passed through said registering openings and having flanged portions gripping the plate and the legging

body for securing the parts together, and a strap having one end secured to the legging body and its opposite end extended successively through said eyelets and having a series of openings for selective engagement 60 with said stud.

3. A legging comprising a body portion, a plate, a plurality of registering spaced openings in the body portion and the plate, a stud carried by the plate and extending 65 through the body portion intermediate the spaced openings, and a strap extending through said registering openings and engaged with said stud.

4. A legging having a pair of spaced 70 openings, a stud positioned between said openings, and a strap extending through said openings and engaged with said stud.

5. A legging having a pair of spaced 75 openings, a stud positioned between said openings, and a strap extending through said openings and provided with an opening fitted over said stud.

6. A legging having a pair of spaced slots, eyelets in said slots and having flanges engaging the interior and exterior, respectively, of the legging, a stud secured to the legging and positioned between said slots, and a strap extended successively through 80 said slots and having a part engaged with 85 said stud.

7. A legging having a pair of spaced slots, a stud having an enlarged contractile head, said stud secured to said legging and positioned between said slots, and a strap extended successively through 90 said slots and having a part engaged with said stud.

8. A legging comprising a fabric body portion, a plate positioned upon the interior of said fabric body portion and having a 95 stud penetrating the fabric body portion and extending externally therefrom, spaced registering openings through the body portion and the plate, means for securing the plate to the body portion, and a strap having a portion extended through the spaced 100 registering openings and having a part engaged with said stud.

In witness whereof I have hereunto set my hand this 8th day of April, 1918.

H. W. COOK.

Witnesses:

E. A. THOMPSON,
ALICE M. CANNON.
